UNITED STATES PATENT OFFICE.

FREDERICK TICHY, OF ASTORIA, NEW YORK, ASSIGNOR TO WAPPLER ELECTRIC COMPANY, INC., A CORPORATION OF NEW YORK.

SUPPORTING COLUMN FOR X-RAY TUBES AND ANALOGOUS MEMBERS.

Application filed September 2, 1922. Serial No. 585,867.

To all whom it may concern:

Be it known that I, FREDERICK TICHY, a citizen of the United States, residing in Astoria, in the county of Queens and State of

5 New York, have invented certain new and useful Improvements in Supporting Columns for X-Ray Tubes and Analogous Members, of which the following is a full, clear, and concise description.

10 My invention relates to supporting columns for X-ray tubes and analogous members; that is, to devices which are used after the manner of a column or post, for supporting devices, such as X-ray tubes and parts associated therewith, in such manner as to allow the X-ray tube and other parts or mechanism equivalent to the X-ray tube and the parts associated therewith, to be adjusted into different positions required in

15 practice, the adjustment admitting of considerable refinement and being of such character that when the adjustment is once made, various movable parts may be locked firmly in position.

20 My improved supporting column and parts associated therewith are for general use, but are specially adapted for use with X-ray tubes, for instance in making stereoscopic displacements.

25 Reference is made to the accompanying drawing forming a part of this specification, and in which like reference characters indicate like parts throughout the several figures.

30 Figure 1 is a fragmentary side elevation of my device, certain parts being broken away and others appearing in section.

Figure 2 is a section on the line 2—2 of Figure 1, looking in the direction indicated by the arrows.

35 Figure 3 is a section on the line 3—3 of Figure 1, looking in the direction indicated by the arrows.

40 Figure 4 is a section on the line 4—4 of Figure 1, looking in the direction indicated by the arrows.

45 Figure 5 is a side elevation of the device, showing it as it would be seen by a person standing at the left of Figure 1 and looking at the mechanism shown in that figure.

50 Figure 6 is a fragmentary section showing certain parts appearing in the upper portion of Figure 1, but upon a scale somewhat larger than that of said Figure 1.

55 Figure 7 is a fragmentary section through

a portion of the mechanism appearing in Figure 2, but showing the same upon a scale somewhat larger than that of said figure.

60 Mounted upon a base 6 and extending upwardly therefrom is a column 7, having a general tubular form and serving as a post. Secured adjustably but firmly upon this column is a collar 8, held in position by a set screw 9. Mounted loosely upon the top of 65 the column is a cap 10. Secured to this cap and extending downwardly therefrom are a pair of side rails 11 and 12. The lower ends of these rails are by means of bolts 13 secured firmly to the collar 8. For facilitating this purpose the collar 8 is provided with slotted extensions 14, into which the lower ends of the rails 11 and 12 are neatly fitted.

70 Mounted upon the cap 10 is a bearing 16, carrying a pin 17, and fitted upon this pin is a pulley 18. Engaging the pulley 18 is a cord 19 a portion of which extends down into the column 7 and carries a weight 21, another portion extending downwardly and 75 being connected by an anchorage 20 with a spider 22, serving as the frame of a carriage and movable vertically in relation to the column 7, as hereinafter described. The weight 21 thus serves as a counterbalance 80 for the carriage.

85 The spider 22 carries a bearing 23, having the form of a sleeve, as shown more particularly in Figures 1 and 2. Extending through the bearing 23 is a round bar 24, 90 which may be locked rigidly in position by aid of a set screw 25. The bar 24 serves as a mounting for supporting a fluorescent screen of the usual or any preferred construction.

95 Revolubly mounted upon the spider 22 are track wheels 26, 27, 28, and 29, the track wheels 26 and 28 engaging the edges of the rail 11, and the wheels 27 and 29 similarly 100 engaging the edges of the rail 12. Each track wheel 26, 27, 28 and 29 is mounted upon a pintle 30, provided with a portion 31 of reduced diameter, extending through a hole in the spider 22 and secured firmly in position by a nut 32.

105 The spider also carries four bosses 33, 34, 35 and 36, each provided with a portion 37 of reduced diameter extending through a hole in the spider and held in position by a nut 38. The bosses 33, 34, 35 and 36 slidably 110

engage the adjacent edges of the rails 11 and 12. Thus the track wheels 26 and 27 are paired with the bosses 33 and 34, and the track wheels 28 and 29 are similarly paired 5 with the bosses 35 and 36. For reasons hereinafter stated, however, the bosses bear little or no working strain, practically all of the working strain being borne by the track wheels. Each of the track wheels is provided with a ball bearing 39, as may be understood from Figure 3. With this arrangement there is a minimum of friction offered by the rotation of the track wheels.

The spider 22, with its track wheels 26, 15 27, 28 and 29 and bosses 33, 34, 35 and 36, constitutes a carriage, which may as a unit be raised or lowered relatively to the column 7.

The boss 33 carries a hook 40, to which a 20 cord may be attached for raising or lowering the carriage. However, the carriage may be raised or lowered directly by hand, so that the use of the cord is not essential.

In order to provide for moving the carriage slightly either upward or downward at the will of the operator, so as to make a stereoscopic displacement of the X-ray image, I use a rod 41, extending loosely through the boss 33, and held in position 25 by a butterfly set screw 42, which extends axially into the boss 33. When the set screw 42 is forced tightly against the gage rod 41, the latter is locked firmly in relation to the boss 33, but when the set screw 30 is loosened the boss 33, and consequently the carriage 32, may be moved relatively to the gage rod 41. The gage rod carries two stop pins 43, 44, each extending diametrically through it as indicated more particularly in Figure 6. The stop pins 43 and 45 limit the travel of the boss 33 and the gage rod 41 relatively to each other. A slide 45 is fitted upon the rail 11, and has the general form of a rather flat collar encircling the same. The slide 45 may be moved 50 vertically in relation to the rail 11 and column 7. The slide carries a clamping bolt 46, and by rotating this bolt slightly the collar 45 may be secured rigidly upon the rail 11, or rendered loose relatively thereto. The rail 11 is provided with a scale 47, preferably graduated as shown, to enable the operator to determine the precise position of the slide 45 relatively to the column 7 and rail 11. 55 The scale also serves as a guide for the operator in order to assist him in adjusting the slide 45 to a predetermined height relatively to the supporting column. The slide 45 carries the gage rod 41, which for this purpose is provided with a base portion 48, a shank portion 49 and a nut 50, as indicated more particularly in Figure 6. The carriage also carries a pointer 51, to assist the operator in making the readings from the 60 scale 47.

In practice the operator first determines by aid of the scale 47 and pointer 51 the position to be occupied by the slide 45. Then he loosens the slide by slightly turning the clamping bolt 46, moves the slide 70 into the position desired, and locks it in position by turning the clamping bolt 46. This prevents the carriage 42 from moving vertically in relation to the supporting column 7, except to an extent 75 that the boss 33, carried by the carriage, can move within the limits of travel allowed by the stop pins 43, as may be understood more particularly from Figures 4 and 6. The operator next displaces the carriage vertically through the interocular distance; that is, the distance through which the X-ray tube must be moved in order to make a pair of stereoscopic views or images; and then by tightening the set screw 42 80 locks the carriage securely in position. By loosening the set screw 42, shifting the position of the carriage within the limits thus contemplated and then tightening the set screw, the operator can quickly make the 85 required displacement of the X-ray table and carriage.

Four track wheels 52, 53, 54 and 55, and four bosses 56, 57, 58 and 59 are mounted upon the spider 22, and, generally speaking, 90 are very much like the four track wheels 26, 27, 28 and 29 and the four bosses 33, 34, 35 and 36. A pair of movable rails are shown at 60, 61 and are so disposed as to extend horizontally. The bottom of the rail 60 engages the boss 58 and the track wheel 54, the top of this rail engaging the track wheel 52 and the boss 56. The top of the rail 61 engages the track wheel 53 and the boss 57. The rails 60 and 61 are 100 provided with terminal eyes 63 and 64, and a cross bar 65 extends through these terminal eyes and also through a pair of eyes 66, with which the spider 22 is provided. Mounted upon the rails 60 and 61, at the 105 ends thereof opposite the cross bar 65, is an X-ray tube supporter 67, carrying an X-ray bowl 68 in which is mounted an X-ray tube 69. The X-ray bowl 68 and X-ray tube 69 are adjustable into a number of different 110 positions by aid of adjusting mechanism 70.

For the purpose of balancing the weight of the X-ray bowl 68 and various other parts adjacent thereto carried by the rails 60 and 61 I provide a number of metallic 115 weights 71, as may be understood more particularly from Figures 1 and 5. These weights are provided with slots 72, and by aid thereof are mounted upon a cross bar 73, this cross bar serving as an axle 120 for the track wheels 52 and 53, as indicated more particularly in Figures 2 and 5. As a general rule the X-ray bowl 68 slightly overbalances the weights 71, so that the excess of the weight causes the rails to bear 125

against the track wheels 52, 53, 54 and 55, rather than against the bosses 56, 57, 58 and 59. The track wheel just mentioned being provided with ball bearings like that of the track wheel 28 shown in Figure 3, the friction due to movement of the rails 60, 61 is reduced to a minimum. The result is that the two rails just mentioned may be shifted freely in either of two directions, or in other words that they may be moved endwise back and forth, in the horizontal direction in which they extend. When thus shifted in position they are moved practically as a unit. Mounted upon the horizontal rail 60 is a slide 74, having a form and function analogous to that of the slide 45 above described, and shown in the upper portion of Figure 1. The slide 74 carries a set screw 75 by aid whereof it may be locked in different positions relatively to the rail 60, and released from said positions at the will of the operator. A gage rod 76 is carried by the slide 74, to which it is secured by aid of a nut 77. The gage rod 76 extends loosely through a hole in the boss 56, the direction of the hole through the boss being diametrical. The gage rod 76 carries a pair of stop pins 77, 78, for limiting the travel necessary for stereoscopic displacement of the slide 74 and the box 56 relatively to each other. The gage rod 76 is provided with an indicating mark 79.

When the slide 74 is loose relatively to the rail 60, the rails 60 and 61 are free to travel endwise, as above described, to an extent limited in practice by the length of the rails. When, however, the slide 74 is clamped rigidly upon the rail 60 by means of the set screw 75, the rails 60 and 61 can still move lengthwise, but only to an extent limited by the length of the gage rod—or, in other words, the distance between the stop pins 77 and 78. This is the interocular distance, above explained. The boss 56, being a part of the carriage and thus having no horizontal movement, acts as a limiting stop for the stop pins 77 and 78.

The operation of the parts just described may be readily understood from an inspection of Figures 4 and 7. In order to shift the rails 60 and 61 endwise, and to adjust them accurately so as to support the X-ray tube holder in a predetermined position, the operator proceeds as follows:

If the slide 74 happens to be tight upon the rail 60, he turns the set screw 75 so as to loosen the slide. He then moves the rails 60, 61, as a unit, sliding them endwise to the extent required. He next adjusts the slide 74 in such position that the indicating mark 79 upon the gage rod 76 is inside of the hole through the boss 56, so that the stop pins 77, 78, are spaced at about equal

distances upon opposite sides of the boss. The operator turns the set screw 75, so as to clamp the slide 74 rigidly in position upon the rail 60. This done the rails 60 and 61 can still be moved endwise, but as above explained, only to the limit permitted by the distance between the stop pins 77 and 78. If this distance is, say, three and one-half inches, and the boss 56 has a diameter of one inch, the rail will have the stereoscopic travel of two and a half inches, and if the mark 79 be located at or near the axial center of the boss 56 the rails 60 and 61 may be moved to a distance of an inch and a quarter in either of two directions. Thus it will be seen that the X-ray tube holder supported upon the rails as above described, may be positioned with great accuracy relatively to the column 7 and to the position of the X-ray table, not shown, and may readily be moved the precise distance required for interocular displacement in stereoscopic work.

By means of a screw handle 80 the X-ray tube holder can be loosened so that it may be rotated around the pin 81 as a center.

A feature of considerable importance is the fact that the horizontal framework, comprising the horizontal rails 60 and 61 and their immediate connections, may as a unit be turned relatively to the supporting column 7, and thus adjusted in an infinite number of different angular positions relatively thereto.

In order to shift the horizontal framework in the manner thus contemplated the set screw 9 is loosened, thus loosening the collar 8 relatively to the supporting column 7. Since the cap 10 rests loosely upon the upper end of this column, the horizontal framework including the rails 60 and 61 may as a unit be now turned relatively to the supporting column, or adjusted into any desired angular position around this column as a center. This done, the set screw 9 is tightened so that the horizontal framework is now held firmly in the position into which it is thus placed. Such being the case, the tube supporter and the X-ray tube may be adjusted accordingly, at any desired angle around the column 7 as a center.

The adjustments just described are accomplished without the necessity for straining or disfiguring any of the parts, and may be made with the greatest accuracy.

As a result of this arrangement, the supporting column may be polished, lacquered, varnished or painted, so as to present an attractive appearance, and can retain such appearance after long periods of constant use. This is because the rotational or angular adjustments, as well as the vertical and horizontal adjustments, of the carriage and other parts may be made without any ne-

cessity for scratching or otherwise injuring the surface of the supporting column.

I do not limit myself to the precise mechanism shown, as variations may be made therein without departing from my invention, the scope of which is commensurate with my claims.

Having thus described my invention, what I claim as new and desire to secure by Letters Patent is as follows:

1. In an apparatus of the character described the combination of a supporting column, rails mounted upon said supporting column and extending in the direction of the length thereof and parallel with each other, means controllable by the operator for shifting said rails into different angular positions of adjustment around said supporting column as a center, a carriage mounted upon said rails and movable in the direction of the length thereof, a frame mounted upon said carriage and movable relatively thereto, and a member mounted upon said frame for the purpose of carrying an X-ray tube or the like.

2. In an apparatus of the character described the combination of a supporting column of substantially tubular form, a cap mounted loosely upon one end of said supporting column, a collar loosely encircling said supporting column, a pair of rails extending from said cap to said collar and disposed parallel with each other and with said supporting column, so that said rails, said cap and said collar may be turned relatively to said supporting column, means controllable by the operator for clamping said collar in different positions into which it is thus turned, a carriage mounted upon said rails and movable by the operator in the direction of the length thereof, and a member mounted upon said frame for the purpose of supporting an X-ray tube or the like.

3. In an apparatus of the character described the combination of a supporting column of substantially tubular form, a pair of rails mounted upon said supporting column and revoluble relatively thereto so that they may be turned into different angular positions upon said supporting column as a center, means controllable by the operator for securing said rails in the different positions into which they are thus turned, a carriage mounted upon said rails and movable relatively thereto in the direction of the length of said last-mentioned rails, a framework mounted upon said carriage and movable relatively thereto in directions crossing the length of said rails, and a holder mounted upon said framework for the purpose of supporting an X-ray tube or the like.

4. In an apparatus of the character described the combination of a supporting column, a pair of rails carried by said support-

ing column and disposed parallel with said supporting column and with each other, means controllable by the operator for turning said rails bodily into different positions relatively to said supporting column while maintaining said rails parallel with each other and with said supporting column, a carriage mounted upon said rails and movable into different positions along the same, means controllable by the operator for securing said carriage in any of said last-mentioned positions, rails mounted upon said carriage and movable lengthwise relatively thereto, and supporting mechanism carried by said last mentioned rails for the purpose of supporting an X-ray tube or the like, said supporting mechanism being movable toward and from said supporting column.

5. In an apparatus of the character described the combination of a supporting column, rails mounted upon said supporting column and parallel therewith, means for shifting said rails bodily so as to bring them into different angular positions of adjustment relatively to said supporting column, a carriage mounted upon said rails and movable relatively thereto into different positions of adjustment, an X-ray tube supporter, means for supporting said X-ray tube supporter upon said carriage, and mechanism controllable by the operator for enabling him to move said carriage and thus to space the X-ray tube supporter at different distances from said supporting column.

6. In an apparatus of the character described the combination of a pair of rails, means for supporting said rails parallel with each other and so that they extend substantially in a vertical direction, a carriage mounted upon said rails and movable in the direction of the length thereof, rails carried by said carriage and extending in a direction crossing the length of said first mentioned rails, and a supporting mechanism mounted upon said second mentioned rails and movable relatively thereto for the purpose of supporting an X-ray tube or the like.

7. In an apparatus of the character described, the combination of a supporting column normally extending in a vertical direction, rails supported by said supporting column and extending parallel therewith, a carriage mounted upon said rails and movable in the direction of the length thereof, means controllable by the operator for securing said carriage fixedly in position at heights predetermined by the operator, a supporting member mounted upon said carriage for the purpose of supporting an X-ray tube or the like, a frame structure carrying said supporting member, said frame structure extending from said carriage and being supported thereby, said frame structure being movable relatively to

said carriage for the purpose of allowing said supporting member to be spaced from said supporting column by different distances to be determined by the operator, and 5 means for locking said frame structure relatively to said carriage.

8. In an apparatus of the character described, the combination of a supporting column, a pair of rails mounted upon said 10 supporting column, said rails extending vertically and being parallel with each other, a carriage movable relatively to said supporting column and provided with track rollers engaging said rails, so that said carriage 15 may be moved relatively to said rails and said supporting column, and a pair of other rails carried by said carriage and crossing the length of said first mentioned rails, an X-ray tube holder mounted upon said second 20 mentioned rails and supported thereby, and means controllable by the operator for shifting said second mentioned rails relatively to said carriage.

9. In a device of the character described 25 the combination of rails spaced apart and disposed parallel with each other, means for supporting said rails so that they extend vertically, a carriage mounted upon said rails and movable in the direction of the 30 length thereof, means controllable at the will of the operator for clamping said carriage in different positions along said rails, so as to adjust the height of said carriage relatively to said rails, an X-ray tube holder 35 and a frame structure connected with said X-ray tube holder for supporting the same, said frame structure engaging said carriage and being movable bodily in relation thereto so as to control the proximate distance 40 from the X-ray tube holder to the rails, a slide mounted upon said frame structure and movable relatively thereto, means for clamping said slide rigidly in relation to 45 said frame structure so as to prevent the frame structure from moving except as the slide is moved, and means controllable at the will of the operator for limiting the travel of the slide, so as to limit the extent 50 to which the frame structure can be moved relatively to said rails.

10. In an X-ray apparatus the combination 55 of a supporting column, a pair of rails carried by said supporting column and disposed upon opposite sides thereof, said rails being parallel with each other and normally extending vertically, a carriage mounted upon said rails and movable in the direction of the length thereof, said carriage being thus movable vertically, anti-friction wheels 60 mounted upon said carriage, a pair of rails engaging said anti-friction wheels and supported by said carriage, said last-mentioned rails being connected together and movable bodily lengthwise in a direction crossing the length of said first mentioned rails and said

supporting column, an X-ray tube holder mounted upon said second mentioned rails and by movements thereof adjustable toward and from said first mentioned rails and said supporting column, a slide mounted upon one of said second mentioned rails and movable relatively thereto by the operator, means controllable by the operator for locking said slide rigidly to the rails upon which it is mounted so as to prevent the said rails from moving except with the slide, and means controllable at the will of the operator for limiting the travel of the slide relatively to the position of said first mentioned rails and said supporting column. 80

11. In a device of the character described the combination of a pair of rails, means for supporting said rails so that they are parallel with each other, a carriage provided with track wheels and bosses for engaging said rails, so as to permit the carriage to be shifted along the rails and to prevent the carriage from being tilted, other track wheels and bosses mounted upon said carriage, a pair of other rails engaging said last mentioned track wheels and bosses, and thus supported by said carriage, said second mentioned rails being movable endwise in a direction crossing the length of said first mentioned rails, an X-ray tube holder mounted upon said second mentioned rails and movable bodily therewith to different distances along first mentioned rails, a slide connected with one of said second mentioned rails and normally movable in relation thereto, means controllable by the operator for locking said slide to the rail upon which it is mounted, so as to prevent movements of said second mentioned rails except as said slide is moved, and means controllable by the operator for limiting the travel of said slide. 85

12. In a device of the character described the combination of a supporting column, a carriage supported by said supporting column, means controllable by the operator for shifting said carriage into different positions relatively to said supporting column, wheels and bosses mounted upon said carriage, rails engaging said wheels and bosses and thus supported by said carriage, said rails extending crosswise of the length of said supporting column and being movable in the general direction of their own length, a slide mounted upon one of the rails and normally movable in relation thereto, means for enabling the operator to lock said slide rigidly to the rail upon which it is mounted, so that said rails as a unit can move only to the extent permitted by movement of the slide, a gage rod connected with said slide and movable therewith, a stop pin carried by said gage rod, a fixed member located partially within the path of travel of said stop pin for the purpose of limiting the

movement of said gage rod and thereby limiting the movement of said rail, and an X-ray tube holder mounted upon said rails.

13. In a device of the character described, 5 the combination of a supporting column, a rail mounted thereupon, a carriage supported by aid of said rail and movable relatively to said supporting column and said rail, a slide mounted upon said rail and normally movable relatively thereto, means controllable by the operator for locking said slide in different positions along said rail, a gage rod carried by said slide, and means for limiting the travel of said carriage relatively to said gage rod.

14. In a device of the character described 10 the combination of a supporting column, a pair of rails mounted upon opposite sides of said supporting column and disposed parallel with each other, a carriage mounted upon said rails and movable in the direction of the length of said rails and said supporting column, a slide, means controllable by the operator for fixing said slide in different positions relatively to the length of said rails, and mechanism connected with said slide and with said carriage for limiting the extent to which said carriage may be moved relatively to the supporting column and 20 rails, supporting members carried by said slide, and an X-ray tube holder mounted upon said supporting members.

15. In a device of the character described 25 the combination of a supporting column, a pair of rails carried by said supporting column and disposed parallel with each, a carriage mounted upon said rails and movable in the direction of the length thereof, means for locking said carriage in different positions related to the length of the rails and supporting column, frame mechanism carried by said carriage and extending longitudinally therethrough in a direction crossing said rails and supporting column, said frame mechanism being movable bodily in the direction in which it extends, an X-ray tube holder carried by said frame mechanism and by movements thereof adjustable toward and from said rail and supporting 30 column, a gage rod, means controllable by

the operator for connecting said gage rod with said frame mechanism in different positions along the frame mechanism, and mechanism mounted upon said carriage and coacting with said gage rod for limiting the travel of said frame mechanism relatively to the rails and supporting column.

16. In a device of the character described 35 the combination of a supporting column, a pair of rails mounted upon opposite sides of said supporting column and disposed parallel with each other, one of said rails being provided with a gage, a carriage mounted upon said rails and movable in the direction of the length thereof, said carriage being provided with an indicating member coacting with said gage for enabling the operator to define the position of the carriage relatively to the rails, a gage rod, means controllable by the operator for securing the gage rod in different positions relatively to the length of the rails, mechanism mounted upon said carriage and coacting with said gage rod for limiting the travel of said carriage relatively to said gage rod, and means controllable by the will of the operator for securing said carriage to said gage rod and thus locking said carriage relatively to said rails.

17. In a device of the character described 40 the combination of a pair of rails parallel with each other, means for supporting said rails, a carriage mounted upon said rails and movable in the direction of the length thereof, means controllable by the operator 45 for limiting the travel of the carriage relatively to the rails, frame mechanism mounted upon the carriage and movable relatively thereto in a direction crossing the length of the rails, an X-ray tube holder mounted upon said frame mechanism and movable toward and from said rails, stop mechanism controllable at the will of the operator for limiting the travel of said supporting mechanism relatively to said rails, and means controllable by the operator for clamping said stop mechanism so as to render said frame mechanism immovable relatively to said rails.

FREDERICK TICHY.
